UNITED STATES PATENT OFFICE.

SAMUEL WILLIAM MAQUAY, OF TEDWORTH SQUARE, LONDON, ENGLAND.

PRIMARY BATTERY.

SPECIFICATION forming part of Letters Patent No. 368,099, dated August 9, 1887.

Application filed April 14, 1886. Serial No. 198,848. (No model.) Patented in England December 8, 1885, No. 15,040; in France March 9, 1886, No. 174,655, and in Germany March 11, 1886, Nos. 37,933 and 38,439.

To all whom it may concern:

Be it known that I, SAMUEL WILLIAM MAQUAY, a subject of Her Majesty the Queen of Great Britain, residing at 22 Redburn Street, 5 Tedworth Square, London, England, have invented a certain new and useful Improvement in Primary Batteries, (for which Letters Patent have been granted to me in Great Britain, No. 15,040, dated December 8, 1885; in France, 10 No. 174,655, dated March 9, 1886; in Germany Nos. 37,933 and 38,439, both dated March 11, 1886,) of which the following is a specification.

This invention has for its object the production of electric currents by an improved method in the construction of the cells, in the material composing the positive and negative elements, and in the manner of applying the exciting liquids so as to produce the least 15 amount of waste and the most powerful lasting effects by a small consumption of the positive elements.

The positive metal may be composed of two parts of lead and ninety-eight parts of commercial zinc coated with mercury and heated 20 until the mercury is intimately mixed with each particle of the alloy. Although this alloy will give good results, I find by experiment that still better results will be obtained 25 by the admixture of a small percentage of tin and mercury to the molten metal, as this will insure a more perfect amalgamation of the metals than if the mercury alone were simply coated on and the whole mass submitted to 30 heat. I therefore prefer to compose the positive element of about one part, by weight, of mercury; two parts, by weight, of tin; two parts, by weight, of lead; ninety-five parts, by weight, of common zinc. The tin being first smelted, 35 the mercury is added and well mixed, and the lead, being melted in a separate ladle, is added and well stirred in. The zinc is melted in a separate ladle, and when at as low a temperature as it will properly melt, the composition 40 is added and well stirred in, so as to mix it completely. It is then either cast into rods or rolled into plates and used in any convenient shape.

When formed in the shape intended for use, 45 a convenient number of plates or rods are

dipped into a bath of pickle made of two parts of sulphuric acid in twenty parts of water and shaken until thoroughly clean, when they are at once plunged into a bath of mercury for a minute, taken out to drain, and submitted to 55 a heat of 100° Fahrenheit for five minutes, when they are again dipped into the pickle and again into the mercury, and again heated until each pound of metal has taken up about one-fourth of an ounce of mercury, when it will 60 be found that the plates, having become amalgamated with the mercury instead of simply plated, will require no further attention for the whole term of their life, care having been taken that the fluid used to excite them in the 65 cells does not become mixed with the fluid of the negative element, as should that happen the plates would require cleaning.

For the negative element I use any convenient one—such as carbon, platinum, &c.— 70 either in plates or in any other form; but I dip a portion of such plates or rods into liquid sulphur, so as to leave a film of sulphur equal to from one-twentieth to one-eighth of the area of the plate or rod, or I place broken granules of sulphur in the cells along with the plates or rods in the same proportion. The sulphur is used to occlude the hydrogen evolved while the battery is at work. The water contained in the exciting solutions is 75 decomposed by the electric current into its elements, the oxygen going to the positive plate, which, as is well known, is gradually oxidized. The hydrogen going to the negative element would, in the ordinary course, gradually accumulate thereon in the form of bubbles, and, being a bad conductor, the power of the battery would gradually be diminished. To avoid this the negative element is coated with sulphur, or sulphur in the form of granules is 80 introduced, and this takes up the hydrogen and leaves the negative element free to act. As sulphur itself is a bad conductor, preferably only a portion of the negative element is coated therewith, although the entire plate 85 may be so coated, if desired.

To clearly explain the construction of the battery reference is made to the accompanying drawings, which form part of this specification, and in which— 100

Figure 1 represents a sectional elevation of the battery-box, showing the arrangement of the cells with the negative plates in position; Fig. 2, a sectional elevation on the line $x-x$ of Fig. 3, and Fig. 3 a plan view on the line $y-y$ of Fig. 1.

In the formation of the battery I use double cells, the inner one being of any suitable porous material; but preferably its two walls are formed of a mixture of two parts of carbon in fine dust mixed with "slip" equal to six parts of the usual material of which cells are made, and baked at the usual temperature, but without the presence of air, so that the carbon is not consumed.

I find by experiment that if the cell-walls are made solely of carbon, difficulty is experienced in getting them to stand for any lengthened period. These porous cells, as will be seen in the drawings, are formed by two flat plates, K, of the porous material sliding in the ebonite battery-case A.

The outer cells, G, each extends under the respective cell or compartment K and upward at the sides thereof, and are made of any convenient material—such as glass, porcelain, wood, &c.; but preferably I use vulcanite or ebonite, or any other such non-conducting light material. The cells are placed side by side, either in a circle or square, or in any convenient shape, and each cell has a communication, H, from one to the other within about half an inch of the bottom, the dividing-wall through which the communication or passage H extends being thickened, thus making one part of the cell or compartment G shorter than the other part, as shown in Fig. 3, and this communication between each cell is so arranged that it can be closed or opened at will by means

of the plungers E, which are located in the thickened walls and are arranged to open or close the passages H in the manner hereinafter fully described, it being understood that the negative cells have only a communication with other negative cells, and the positive cells can only communicate with the positive. This communication from cell to cell is made to enable them to be filled or emptied or flushed out with water without interfering with or removing the battery-plates I J, and the arrangement is such that all of the said plates can be removed at the one operation, so as to clean or renew them when required. This I accomplish by attaching the tops of the plates I J, as well as the plungers E, to a top plate, D, of ebonite or other material, which may be lifted entirely out of the battery-case or may be raised slightly by the eccentric C, the shaft of which passes through the battery-case.

When the ebonite or other plungers E are raised, there is free communication between the cells by means of openings H. When the eccentrics C are turned down, the plungers E (the ends of which are preferably coated with an admixture of tallow and paraffine) close the communicating channels H and the plate D, which is provided with a suitable under

packing, D', is also held firmly against the top of the cells and prevents the liquid from escaping during transport. The connections between the battery-plates are preferably above plate D, so as to be clear of the acids.

The solution I use for the outer or positive cell is one part of sulphuric acid in twenty parts of water. I may also use a solution of common salt, the solution being composed of the amount of salt that would be taken up by water at a temperature of 60° Fahrenheit.

For the liquid in the porous or negative cells I may use any that will most readily absorb the hydrogen and prevent polarization; but I prefer when using carbon plates to use a solution of bichromate of potash, thirty-five to forty parts; sulphuric acid, ten to twenty parts, and nitric acid, forty to fifty-five parts.

By using this solution a very small proportion of acid fumes escapes and water is formed; but as a further precaution against the faint acid smell I place a small tray, B, made of ebonite, inside the battery-case and over the cells and plate D, and in it I place any absorbents which will most readily affect the acid fumes or water. I at present prefer to use pieces of pumice-stone steeped in strong sulphuric acid and mixed with some powdered sulphur, when all fumes or vapors are at once taken up if the proportions of the absorbents are properly regulated to the size of the battery. The size of the absorbing-tray I find most convenient is one that will cover about two-thirds of the space occupied by the top of the cells. I form the battery of any number or size of cells, according to the work proposed to be done, and I make each set in a separate case for convenience of transport or for lighting table or bed-room lamps, &c.

In the drawings a twelve-cell battery is represented; but I do not confine myself to any particular number of cells. This battery may be conveniently formed out of ebonite, all made in one mold, the cells being in four rows, three in each row, end to end, the side walls of the cells being about one-eighth of an inch thick, the end wall joining two cells together being five-eighths of an inch thick. In the ends of each cell and along the bottom I run two grooves, one-sixteenth of an inch deep and placed five-eighths of an inch from each other. Into these grooves I slide the porous plates K and fix them firmly with an acid-proof cement. This forms the porous compartment for each cell. In the thickened portion of the ebonite cell I drill holes straight to within an inch of the bottom of each cell, and then with a cone shape for the next half-inch. In these holes I fit the plungers E, of ebonite, turned into a cone shape at the end, so as to fit accurately. I then remove the plungers and drill a hole, H, one-eighth of an inch in size, from one cell to the next, and when the plungers E are replaced they completely stop the holes H, as before described.

When the plungers E are held up, the screw-plug M may be removed and the cells charged

through the opening, while through the discharge-pipes T (provided with the gage S) all the cells may be emptied and the battery flushed out.

5 Having thus described the nature of the invention, what I claim, and desire to secure by Letters Patent, is—

1. The method of amalgamating a positive element for batteries, consisting in coating said 10 element with mercury and then subjecting the coated element to the action of heat, substantially as described.

2. The method of amalgamating a positive element for batteries, consisting in treating the 15 same with acid, then coating it with mercury, and then subjecting the coated element to the action of heat, substantially as described.

3. A positive element for batteries, consisting 20 of a metallic alloy and mercury forming an amalgam with said alloy, substantially as described.

4. A positive element for batteries, consisting 25 of an alloy of zinc, lead, and tin amalgamated with mercury, substantially as described.

5. An electro-negative element for batteries, consisting of a suitable electro-negative material provided with a partial coating of pure or uncombined sulphur, substantially as 30 described.

6. A battery consisting of cells having compartments containing the positive elements and

fluid, and communicating directly one with the other by suitable passages, compartments containing the negative elements and 35 fluids and communicating directly one with the other by suitable passages, and means for closing the passages between the compartments, substantially as described.

7. A battery consisting of cells with compartments containing the positive elements and fluid and communicating one with the other by suitable 40 passages, compartments containing the negative elements and fluid and communicating one with the other by suitable 45 passages, and plungers operating to open or close said passages, substantially as described.

8. A battery consisting of a series of cells with communicating compartments containing the positive elements, communicating compartments containing the negative elements, 50 a top plate carrying plungers for opening or closing the communications between the compartments, and also carrying the battery-plates, and a tray for absorbent material above 55 said plates, substantially as described.

In witness whereof I have hereunto set my hand in the presence of two subscribing witnesses.

SAMUEL WILLIAM MAQUAY.
